DEVICE FOR BREAKING UP LIQUID DROPLETS IN A GAS STREAM

James R. Alburger, Los Angeles, Calif., assignor of one-half to Irl R. Goshaw, Beverly Hills, Calif.

Application November 29, 1944, Serial No. 565,771

4 Claims. (Cl. 48—180)

1

This invention relates to atomization devices, and particularly to an adjunct to a carburetor for the purpose of improving vaporization and the mixture of gasoline and air.

Since the advent of internal combustion motors, especially for automobiles, many modifications have been made to the method of and means for supplying a gasoline and air mixture to the cylinders, and especially by attachments or adjuncts to the carburetor. Many of these adjuncts have taken the form of rotating blades of various forms and arrangements, which are rotated by the flow of the air and gasoline mixture through the carburetor or intake manifold. In practically all instances, such attachments have provided increased atomization of the gasoline by breaking up the globules or droplets of gasoline, which improves the distribution of the mixture to the cylinders and improves combustion within the cylinders.

The prior art devices of this type have had a very critical fault, however; namely, that they rotate on bearings either arranged vertically or horizontally in the carburetor or manifold. This is probably the chief reason why such devices have not been more universally adopted, since they rotate at high speeds and with lubrication difficult, the bearings have a short life, thereby causing stoppage and thus requiring frequent replacement. In some instances, the blades become broken and are drawn into the valves and cylinders. It is, of course, undesirable to have an attachment which is subject to such short life, and which may, at any time, cause damage to the motor.

The present invention is directed to a bearingless rotating device, that is, there is no direct contact between rotating parts, which performs the functions of breaking up the globules of gasoline into finer particles, reduces overloading of the cylinders, and varies the ratio of gasoline to air in a direction to improve combustion and provide greater mileage per gallon of gasoline. This is particularly true for low grades of gasoline. The main feature of the device is that the rotor floats in the mixture stream passing downwardly from the carburetor and thus operates on the Bernoulli principle. The blades are given a slight twist which imparts motion to the rotor of the device, while the differential in pressure provided between the upper and lower surfaces raises the rotor above its rest support, a moving layer of gasoline and air mixture separating the stator and rotor during rotation. In one modification of the invention, a pin is provided for centering the

2

rotor with respect to the stator, while in another modification centering is obtained by the conical form of the stator or rotor.

The principal object of the invention, therefore, 5 is to improve atomization and particularly the carburetion of internal combustion motors.

Another object of the invention is to provide an improved method of and means for atomizing or mixing gasoline with air.

10 A further object of the invention is to provide an improved attachment to an internal combustion motor carburetor for breaking up gasoline globules for better distribution and combustion.

A still further object of the invention is to provide 15 a rotating element in an air passage which floats on the air stream.

A still further object of the invention is to provide a rotating rotor at a fixed position in a down stream air passage.

20 Although the novel features which are believed to be characteristic of this invention will be pointed out with particularity in the appended claims, the manner of its organization and the mode of its operation will be better understood 25 by referring to the following description read in conjunction with the accompanying drawings forming a part hereof, in which:

Fig. 1 is a cross sectional view of the lower portion of a carburetor showing one modification 30 of the invention in operating position.

Fig. 2 is a plan view of the invention.

Fig. 3 is a cross sectional view showing the invention with its rotor in rest position.

Fig. 4 is a plan view of another embodiment of 35 the invention.

Fig. 5 is a cross sectional view of the embodiment shown in Fig. 4 and taken along the line 5—5 thereof, showing the invention in operating position, and

40 Fig. 6 is a cross sectional view of another form of the modification shown in Figs. 4 and 5 with the rotor in rest position.

Referring now to Figs. 1, 2, and 3 in which like 45 numerals refer to identical elements, the lower portion of a carburetor shown by wall 5 has positioned therein a butterfly valve 6 which is adapted to be actuated about a pivot 7. The intake manifold shown by wall 10 is bolted to the carburetor by bolts 11 and between which is positioned the invention as illustrated in Fig. 1, the ends 16 of the stator 13 being clamped by the bolts 11, and pressed into the usual gasket at this point.

The device consists of five parts; namely, the 55 stator 13 having the elongated end portions 16

and a center disc portion 14 with an opening 15 therein, a U-shaped bracket 17 with its ends attached to the stator at points 18 and 19, the center portion of the bracket 17 carrying a centering pin 21; a washer 22, resting on the bracket 17 and rotatable and held in centered position by the pin 21; and a rotor 23 having a central disc section 24 and two blades 25 and 26, which are twisted at an angle of approximately 15 degrees to the horizontal, the disc portion having four holes 28 therein as shown at 28. Although the holes 2 may vary in number and diameter, the preferred form is illustrated in the drawings.

The passage of the air and gasoline mixture downwardly accomplishes two purposes. First, as it strikes the twisted blades 25 and 26, it rotates the rotor, and as it passes downwardly through the opening 15 in the stator 13, it causes the rotor 23 to be bodily moved upwardly off of the washer 22 so that it rotates without contact with the washer or the stator 13. It may, at times, contact the pin 21 when unequal amounts of the mixture tilt the rotor 24 at intervals. The rotor is bodily translated upwardly by the well-known Bernoulli effect, wherein the velocity of the fluid passing the upper surface of the rotor disc portion 24 is greater than the velocity of the fluid passing the lower side of the rotor, thus causing a differential in pressure in a direction toward the general flow of the fluid. Thus, there is a negative pressure on the upper surface of the rotor as compared with the pressure on the under surface thereof or the normal pressure within the manifold. The result is that the rotor is maintained in a predetermined position adjacent the stator during operation, but separated therefrom by a moving layer of the mixture. The holes 28 increase this pressure differential by permitting some of the fluid to pass through the rotor to cause turbulence on the under side thereof as compared to the uniform flow of the fluid over the upper surface of the rotor. The dimensions of the rotor disc portion 24 have been so proportioned with respect to the dimensions of the blades as to provide sufficient lift to overcome the downward pressure of the mixture on the blades. In this manner, the rotor does not contact the washer 22 or the under surface of the stator 13, thus providing a frictionless bearing.

One embodiment of the invention, wherein the dimensions between the ends of the bracket 17 permit the device to be used in a one and one-quarter inch diameter manifold, has the following dimensions. The disc portion 14 of the stator 13 was .58 inch, while the width of the end portions 16 was .14 inch. The attachment points 18 and 19 on the stator were .547 inch from the center of the disc, while the diameter of the hole 15 was .18 inch in diameter. The entire length of the stator was 3 inches. The stator was made of tempered clock spring steel .012 inch thick.

The rotor was also made of tempered spring steel having a thickness of .008 inch with a diameter between the ends of blades 25 and 26 of 1.02 inches, the diameter of the disc portion 24 was .574 inch, while the width of the blades was .04 inch. The four holes 28 in the central portion of the disc had a diameter of 0.45 inch and were positioned with their centers .07 inch from the center of the disc. The bracket 17 was of soft steel or other similar material having a linear length of 1.95 inches with a width of .14 inch and a 0.36 inch diameter hole at the

center. The pin 21 was of high speed steel drill rod, or piano wire .25 inch long with a diameter of .035 inch. A small indentation may be made in the lower end of the pin to make the fastening of the pin to the bracket 17 more secure when swaged in place. The washer 22 was of steel having a diameter of approximately one-quarter of an inch and a thickness of .03 inch. The above dimensioned device had sufficient lift to maintain it in its floating position over a wide range of air velocities and all those encountered in the carburetors of standard makes of automobiles.

Referring now to Figs. 4, 5, and 6, a second modification of the device is illustrated, the main distinction between this modification and the one shown in Figs. 1, 2, and 3 being the elimination of the centering pin 21 and the formation of the rotor and stator in a conical form to provide a centering action. In Fig. 5, this modification is shown in operating position in a carburetor similar to the first modification in Fig. 1, the carburetor being provided with an air pipe 31 so as to provide a constant and substantially uniform downward stream of air through the center hole 32 of the stator 33. This pipe is unnecessary for ordinary operation, but it can be used to provide a maximum rotation of the rotor at all times. Under the stator 33 is a rotor 34 under which is a bracket 35 similar to the stator, rotor, and bracket of the modification shown in Figs. 1, 2, and 3. However, approximately one-half of the central portion of the disc portions of the rotor and stator are pressed into a conical shape as shown in Fig. 5, with the bracket 35 being similarly formed to provide a stop for the rotor when in rest position, and also to prevent the rotor from getting out of position.

This embodiment of the invention operates in the same manner as the first modification in that the rotor 34 is rotated by the mixture of gasoline and air striking the surface of its twisted blades, while the variation in velocity of the air passing the upper surface of the rotor disc and the velocity of the air passing the under surface of the rotor disc causes a differential in pressure in an upward direction, which raises the rotor off the bracket 35 and adjacent the under surface of the stator, there always being a layer of mixture between the lower surface of the stator and the upper surface of the rotor. Similarly to the rotor 24 of Fig. 3, four holes 36 are provided on the upper flat portion of the rotor to provide turbulence to the mixture on the under side of the rotor to increase the difference between the two velocities. As mentioned above, this difference between velocities causes the pressure differential and provides sufficient lift to raise the rotor even during low mixture velocities through the carburetor and manifold. Although the pipe 31 is not required to obtain the floating action of the rotor, its use will provide a maximum rotation of the rotor at all motor speeds, thereby improving operation.

In Fig. 6 a slight modification of the device of Figs. 4 and 5 is shown wherein the four holes 36 in the rotor have been eliminated, while substantially all of the disc portions 38 and 39 have been pressed into a conical form to provide the necessary centering action. This modification will float its rotor in a normal carburetor, but an auxiliary air supply may be provided by a pipe 31 as shown in Fig. 5 to obtain improved action.

The operation of a device as above described on the gasoline and air mixture is well-known in that it causes greater atomization of the mixture than would otherwise occur by the carburetor action alone, particularly during motor starts. It has been found that it is only necessary for a rotor blade to contact the droplets or globules of gasoline at a high speed to shatter them into fine particles, and that although more blades could be added to the rotor, two have been found to be sufficient to provide a desired breaking up action of the gasoline particles with respect to lift. The device has been found to reduce knocking by better atomization and by simply restricting the flow of gasoline and air mixture to the cylinders during acceleration. That is, when the butterfly valve 6 is opened beyond that required to pass a sufficient amount of mixture to the cylinders, the device reduces the amount actually getting to the cylinders. Another result of the use of the device has been found to be that the engine of the motor will run at a higher temperature by increasing the air to gasoline ratio, which, with low volatile types of gasoline, produces better combustion. Since there are no bearings in the device, there is negligible wear, no lubrication necessary, and very low friction, which permits the device to have a particularly long life.

I claim as my invention:

1. A device for breaking up liquid droplets in a liquid-laden gas mixture, comprising a conduit for said mixture, a substantially flat stator disc adapted to be supported by the walls of said conduit, a central opening in said stator disc, a substantially flat rotor disc not structurally connected to any other element and which is larger in circumference than the central opening in said stator disc and disposed below said stator opening, twisted blades extending outwardly from the periphery of said rotor disc, and a supporting structure depending below said rotor disc and from said stator disc to support said rotor disc only when there is no gas flow through said stator opening, said conduit directing said liquid-laden gas mixture toward said stator, the impingement of said mixture on said blades rotating said rotor disc, and the passage of said mixture through said opening and between said stator and rotor bodily translating said rotor off of said support-

ing structure and to a position immediate adjacent said stator, but separated therefrom by a moving layer of said mixture.

5 2. A device in accordance with claim 1, in which the central portions of said stator and said rotor are shaped in the form of upwardly disposed conical surfaces.

10 3. A device in accordance with claim 1, in which openings are provided in the disc portion of said rotor adjacent and below the opening in said stator disc.

15 4. A device in accordance with claim 1, in which auxiliary means are provided for supplying air to said opening in said stator disc.
